UNITED STATES PATENT OFFICE.

CHARLES WIRT, OF ORANGE, NEW JERSEY.

ELECTRIC INDICATOR.

SPECIFICATION forming part of Letters Patent No. 444,966, dated January 20, 1891.

Application filed January 6, 1890. Serial No. 336,068. (No model.)

To all whom it may concern:

Be it known that I, CHARLES WIRT, a citizen of the United States, residing at Orange, in the county of Essex and State of New Jersey, have invented a certain new and useful Improvement in Electric Indicators, of which the following is a specification.

My invention relates to indicators for electric currents, and has for its object to provide a simple, cheap, and easily-applicable meter. It is illustrated in the accompanying drawings, wherein—

Figure 1 is a plan view of the device with the cover removed. Figs. 2, 3, and 4 are modifications of the armature and conductor carrying the current to be measured.

Like parts are indicated by the same letter in each figure.

A is the bed to which the parts are secured, B portions of a conductor carrying the current to be measured, and C C the binding-posts or clamps by which these portions of the conductor are secured to the device, so as to bring that portion of the device or conductor which actuates the needle in series.

D is a conductor leading to the inside of the coil E, and F is a similar conductor leading to the outside of such coil by means of the binding-post G on one of the clamps H, which hold the coil in position. It is to be understood, of course, that the base A is of insulating material.

J is an arm supported on and rising from the plate K, and L is a shaft delicately pivoted on this plate and arm. To this shaft is secured the index or needle M, and also the armature N, shaped as shown. The index or needle and armature and shaft are thus fixed so as to rotate on an axis which is the center of an arc formed by one end of the nearly elliptical coil. This coil is built up in any desired manner, as of sheets, strips, or wire. The armature is made of soft iron and the index or needle of some light material. The relation of armature and index or needle as to size and weight should be such as that when the device is in an operative position the index or needle points to the zero-mark of the scale O, and this relation may be such that in this event the armature will stand in substantially the position indicated in Fig. 1.

In Fig. 2 the conductor B' is simply a bar with an arc-shaped notch B² therein, concentric with which are journaled the shaft L and armature N.

55

In Fig. 3 the conductor B³ assumes the form of a flat strip with the curved portion B⁴, the modified armature B⁵, and a pivoted needle B⁶, on which such armature is secured.

In Fig. 4 the conductor B is simply provided with a curve B⁷, at the center of which is pivoted the needle. The form of the coil convolution or curve of the conductor could of course be greatly altered, the essential feature being that such conductor or connected device should present a curve at some point along which a curved armature may move in such manner that the opposed surfaces of the armature and curve are substantially parallel during such motion and at a constant dis-

The use and operation of my invention, briefly stated, are as follows: The coil or curved portion or effective part of the conductor is coupled in series with the conductor proper carrying the current to the meter, and the device is fixed in position so as to bring the needle to the zero-point. If now the current be applied, the armature tends to move so as to bring more and more of its surface into prox-

imity with the effective surface of the curved conductor, and thus the needle is carried over the scale to indicate the higher readings.

I claim—

- 5 1. The combination of a conductor, an armature suspended in proximity thereto, and an indicator operated by such armature, said armature free to move only so that each point of its effective surface traverses a path equidistant from that of the current at the effective portion of the conductor.
- 10 2. The combination of a conductor and armature similarly curved, and an indicator operated by such armature, which is suspended so that the opposed points on the effective
- 15

surfaces of the curve are substantially constantly equidistant.

3. The combination of a conductor-coil having in part the form of a cylindrical surface, the remaining portion having some form enclosing more volume than the said imaginary cylinder, with a movable armature curved to a substantially cylindrical form and pivoted on a line which is substantially the axis of the curved part of the cylindrical portion of the coil and armature.

CHARLES WIRT.
